US00D675527S

(12) **United States Design Patent**
Rogers et al.(10) **Patent No.:** US D675,527 S
(45) **Date of Patent:** ** Feb. 5, 2013(54) **CONTAINER WITH CLOSURE**(75) Inventors: **Chris Rogers**, Banbury (GB); **Adrian Jahina**, Olney (GB); **Jon Winter**, Cranfield (GB)(73) Assignee: **Rexam Beverage Can Europe Limited**, Luton (GB)(**) Term: **14 Years**(21) Appl. No.: **29/381,380**(22) Filed: **Dec. 17, 2010**(30) **Foreign Application Priority Data**

Jun. 17, 2010 (EM) 001721192-0002

(51) **LOC (9) CL.** ..... **09-01**(52) **U.S. CL.** ..... **D9/503; D9/443; D9/764**(58) **Field of Classification Search** D9/500, D9/512-505, 516, 537, 539, 544-545, 549, D9/558, 574-575, 763-764, 772, 438, 443, D9/452; 215/379, 382-384; 220/660, 662, 220/669, 675, 569, 906

Primary Examiner — Ian Simmons*Assistant Examiner* — Dana L Meyrow(74) *Attorney, Agent, or Firm* — Ungaretti & Harris, LLP(57) **CLAIM**

We claim the ornamental design for a container with closure, as shown and described.

DESCRIPTION

FIG. 1 is a perspective view of the present invention;
 FIG. 2 is a top view of the present invention;
 FIG. 3 is a side view of the present invention; and,
 FIG. 4 is a bottom of the present invention.
